UNITED STATES PATENT OFFICE

2,502,037

VEHICLE BUMPER JACK

John Erikainen, Pelkie, Mich.

Application January 13, 1947, Serial No. 721,763

2 Claims. (Cl. 254—1)

1

This invention relates to new and useful improvements in jacks and more particularly to a bumper jack for vehicles.

The primary feature of the present invention is to provide a device of the character referred to adapted to hold the jack shaft rigidly in a vertical position under the lifted load and to prevent the upper end of said jack shaft from tipping in any direction.

Another important feature of this invention is to provide a jack of the class described which is quickly and easily collapsible to form a small compact structure which occupies very little space in packing or storing.

A further feature of the present invention is to provide a jack structure comprising means associated with the jack shaft adapted to prevent angular displacement and lateral thrust of the jack shaft in a lifting operation to eliminate the possibility of dangerous tilting thereof.

A still further feature of the present invention is to provide a jack structure of the character referred to that is strong and durable in construction, efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the improved jack constructed in accordance with the present invention;

Figure 2 is a group perspective view thereof in folded position;

Figure 3 is a side elevational view of the jack with parts broken away and shown in section, and

Figure 4 is an enlarged sectional view taken on the line 4—4 of Figure 3.

Referring now to the drawing in detail, wherein for the purpose of illustration I have disclosed a preferred embodiment of the invention, the numeral 5 represents an upstanding circular shaft having its lower end rounded and adapted to fit into a circular recess 6 centrally located in a base designated generally at 7 which is adapted to rest upon the ground or other supporting surface.

Said base preferably has its forward side edges tapering toward the forward edge thereof. The forward side edges are bent upwardly to form

2

flange 8 and the forward edge of said base is bent upwardly to form a flange 9 having notches 10 in each corner thereof.

The rear side edges of said base are bent upward to form flanges 11 which extend slightly above flanges 8, and said rear edges of said flanges 11 are turned inwardly to form substantially channel-shaped members designated generally at 12 between which the lower vertical ends 13 of a pair of upwardly and inwardly inclined arms 14 are pivotally connected on pins 15 carried by said channel members.

The rear edge of said base is bent upwardly to form a curved flange 16 integrally cast with 15 said channel members 12.

Downwardly inclined arms 17 extend radially from the hub 18 of said base and are corrugated or channel pressed to form ribs 19 to strengthen or reinforce said arms.

20 The upper ends 20 of arms 14 are turned outwardly and horizontally and are adapted to be secured by rivets or the like 21 on either side of a hanger arm 22 having its outer end extending horizontally outward from ends 20 and bent 25 upwardly to form a hook 23 which is adapted to engage a rectangular vertical opening 24 in the upper flattened end 25 of shaft 5 when the lower end of said shaft is fitted in the recess 6 in hub 18 as shown in Figure 1.

30 A conventional lifting body 26 may conveniently be formed as a one-piece casting provided with a central bore (not shown) through which the shaft 5 is inserted for operation in the usual manner by a handle 32 in a raising and lowering movement.

35 The upper end of said lifting body 26 is provided with a load engaging laterally projecting seat portion 28 adapted to be brought into engagement with the load to be raised, which for example may be the bumper of a vehicle (not shown).

The device being in a set-up-for-use position as shown in Figure 1 is easily and quickly collapsed by first disengaging the upper flattened 45 end 25 of shaft 5 from hook 23 and swinging the handle and operating lever upwardly; the base 7 is then swung upwardly so that notches 10 engage the arms 14 and the upper edges of flanges 8 rest against said arms 14 as is clearly shown in Figure 2, thereby making two very small portions that are conveniently packed ready for use.

In view of the foregoing description taken in conjunction with the accompanying drawings it is believed that a clear understanding of the device will be quite apparent to those skilled in

this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

What I claim is:

1. A collapsible lifting jack of the class described comprising a base, a pair of upwardly and inwardly inclined arms pivoted at their lower ends to said base, said base being swingable upwardly against said arms, a hub centrally located in said base having a recess therein, an upstanding shaft having one end rounded to fit into said recess, a lifting body including a load engaging member longitudinally movable on said shaft, means for moving the lifting body on the shaft, an eye formed in the upper end of said shaft, the upper ends of said inclined arms terminating in horizontal portions, and a hook held between said horizontal portions and projecting outwardly therefrom, said hook being received by the eye to provide supporting means for said shaft.

25

2. A collapsible jack including a base and an upstanding brace pivoted at its lower end to the base for folding one against the other, said brace including a pair of upwardly converging arms, and recesses provided in said base for engaging the arms in a folded position a vertical jack shaft, and interfitting means between the ends of the shaft and the base and brace respectively to detachably hold the shaft in a non-tilting position on the base, said interfitting means including an opening in said jack shaft, and a hook carried by said brace received in said opening.

JOHN ERIKAINEN.
